UNITED STATES PATENT OFFICE.

JOSEPH ERNEST THORPE, OF VANCOUVER, BRITISH COLUMBIA, CANADA.

RAZOR-STROPPING DEVICE.

Application filed April 20, 1922. Serial No. 555,721.

To all whom it may concern:

Be it known that I, JOSEPH ERNEST THORPE, a subject of the King of Great Britain, residing at the city of Vancouver, in the Province of British Columbia, Canada, have invented certain new and useful Improvements in Razor-Stropping Devices, of which the following is a specification.

My invention relates to improvements in devices for stropping razor blades, with more particular reference to two edged blades such as those used in the well-known Gillette safety razor, and the object of my invention is to provide a simple and practical device by means of which such blades may be resharpened in a highly efficient and convenient manner.

I attain this object by the construction illustrated in the accompanying drawings in which—

Fig. 1 is a perspective view illustrating the use of my invention.

Fig. 2 is a side elevation of the device.

Fig. 3 is an end view.

Fig. 4 is a side view with one side removed.

Fig. 5 is a cross sectional view taken through the line 5—5 in Fig. 4.

Fig. 6 is a plan view with top plate and upper portion of the strop removed.

Fig. 7 is a side view of the blade carrier closed.

Fig. 8 is a plan view of the blade carrier open.

Fig. 9 is an enlarged cross sectional view taken through the line 9—9 in Fig. 7.

Similar numerals of reference indicate similar parts throughout the several views.

The device consists of a box, indicated generally by the numeral 1, of a size adapted to lie comfortably in the palm of the hand, having the sides 2 and 3, the ends 4 and 5, and the top and bottom plates 6 and 7, the ends 4 and 5 being provided with slots 8 and 9 respectively of sufficient length and depth to permit of the passage therethrough of the strop 10, while the bottom plate 7 is cut away at midlength of each longitudinal edge to form gaps 11 and 12, as shown in Fig. 6, and adjacent each gap are erected vertical standards 13 and 14 between which extend and on which are rotatably supported rollers 15 and 16. Rotatably mounted on the inside of the end plates 4 and 5 adjacent the slots 8 and 9 are small diameter rollers 17 and 18 the peripheries of which project

slightly below the upper edge of the slots, while rotatably mounted transversely of the box adjacent the underside of the top plate and towards each end respectively are larger rollers 19 and 20, and around these rollers and the innermost ones 15 and 16 is passed the stropping belt 10, the manner of its arrangement being as shown in Fig. 4, that is, the upper portion of the belt is laid around the upper rollers 19 and 20 and its free ends passed back parallel with the upper portion over the rollers 15 and 16 and under the same to extend under the rollers 17 and 18 out through the respective end slots 8 and 9. One end of the strop is provided with an eyed member 21 so that it may be secured to a hook while its opposite end is provided with a ring 22 in which the finger may be engaged to hold the strop tight when operating the device.

23 indicates a small shaft extending transversely of the box intermediate its length and freely supported at its opposite ends in suitable bearings 24 and 25 formed on the sides 2 and 3 respectively to which shaft are secured the side plates 26 and 27 of the blade carrier rocker, which side plates are provided with downwardly extending slotted arms 28 and 29 in the slots of which are engaged pins 30 and 31 secured to the upper ends respectively of levers 32 and 33, these levers being fulcrumed intermediate their length on the standards 13 and 14 by means of a shaft 34 which extends freely through the standards and to the ends of which the levers are secured. 35 and 36 indicate pins secured into the levers 32 and 33 adjacent their lower ends for a purpose hereinafter described.

The side plates of the blade carrier rocker are connected together by a transverse plate 37 which extends between them, as shown by the dotted lines in Fig. 4 and the full lines in Fig. 5, and this plate has a narrow longitudinal slot 38 formed in it extending from end to end and communicating at each end with wider slots, indicated by the numeral 39, cut in the side plates, so that when the side plates are viewed in side elevation they appear to have inverted T-shaped portions or slots cut out of their upper edges, as will be readily apparent on referring to Figs. 4 and 9. An opening 40 is formed in one side of the device, preferably the right hand side, concentric with the T-shaped slot aforesaid, and this opening is made

large enough to admit the razor blade on its flat and the blade carrier, now to be described.

The blade carrier, shown in Figs. 7, 8, and 9, consists of a narrow lower bar 41 hinged at one end to a plate 42, which plate, when the device is assembled, forms a cover for the opening 40, as indicated in Fig. 2, the opposite end of the bar being provided with an upwardly and backwardly turned member 44 forming a hook on the top side of the bar at its free end. Secured into the bar 41 are three vertical pins 45 spaced to suit the spacing of the three holes found in the razor blade 46 and which pins, when the blade is placed on the bar 41, project through the holes in the blade into corresponding holes 47 formed in an upper bar 48 rigidly secured at one end to the cover plate 42, its opposite end extending close to the point of the hook 44 of the lower bar. This upper bar 48 is preferably wider than the lower bar and is provided on its top side with a guide slot 49 in which is slidably mounted for longitudinal movement a locking bar 50 having an upstanding projection 51 for operating it, and as the construction is such that the outer end of the bar 50 lies opposite the entrance of the hook 44 it will be seen that the bar may be moved forward and backward in the slot 49 to engage in the hook to detachably connect the upper and lower bars together or to be disengaged from the hook so that the bars may be parted from each other, or in other words, the blade carrier may be opened or closed when the locking bar is moved in the required directions.

40 The upper and lower bars 48 and 41 respectively are spaced apart at their outer ends by the thickness of the end 52 of the member 44 remote from its hooked end, as shown in Fig. 7, that is, when the blade carrier is closed the outer ends of the blade 46 and of the upper bar rest on the end 52, and the space between the blade and the lower bar and the width of the lower bar is such as will permit of the outer end of the 45 blade carrier, that is, the end remote from the cover plate 42, being passed through the opening 40 and entered into the T-shaped slot of the side plate 26 and then pushed inwardly under slight hand pressure 50 until the said end enters and is seated in the T-shaped slot of the side plate 27, when the blade will be resting tightly on the upper side of the transverse plate 37 with the lower bar 41 frictionally engaging the underside of the plate. The cover plate 42 is then seated against the side of the box closing the opening 40 and in order to prevent inadvertent outward movement of the blade carrier when the device is being operated 55 the cover plate 42 is provided on its upper

edge with a short tongue 53 adapted to rock with the carrier behind a downwardly extending flange 54 formed on the side of the box, the flange being provided with a notch 55 through which the tongue passes when seating the blade carrier in place. For convenient withdrawal of the carrier to remove or insert a blade the cover plate 42 is provided with a finger ring 56 hingedly connected to it.

The operation of the rocker is effected by means of a bottom plate 58 mounted to lie on the bottom plate 7 of the box, which plate 58 is turned upwardly at opposite ends to form sides 59 and 60 disposed to lie close to the sides 2 and 3 of the box, the upper edges of which sides are turned over inwardly to engage slidably beads 61 and 62 extending longitudinally on the top plate of the box, from which it will be seen that the plate 58 is connected to the box and capable of longitudinal movement with relation thereto. At midlength the plate 58 is provided with upstanding jaw members 63 and 64 projecting through the gaps 11 and 12 of the bottom plate 7 normally engaging the pins 35 and 36 of the levers 32 and 33, while the side 59 is cut away to clear the cover plate 42.

The manner in which the device is used may be briefly described as follows: The blade to be resharpened being placed in the blade carrier and the latter being inserted in the opening 40 and pushed inwardly to be seated on the rocker the member 21 is hooked to a hook or a nail and the strop straightened out and held taut by the left hand, one finger of which is inserted in the ring 22. The box is then gripped by the right hand the thumb of which bears on and grips the side 59 of the plate 58 while the fingers bear on and grip the side 60 and the box is then moved to and fro. At the commencement of each movement of the box, however, the plate 58 moves independently of the box a short distance in advance of the same sufficient to rock the levers 32 and 33 by means of the jaws 63 and 64, as it will be seen on reference being had to Figs. 4 and 6 that the jaws 63 and 64 are free to move longitudinally in the respective slots 11 and 12 the necessary amount required for such independent movement before engaging the respective end edges of the slots to be arrested thereby and move the box. Movement of the levers in one direction rocks the blade rocker in the opposite direction, tilting it so that the opposite edges of the razor blade bear on the under side of the upper portion of the strop and on the upper side of the underneath parallel portion, as shown in Fig. 4, and thus, prior to the actual movements of the box itself, the blade is rocked in opposite directions to bring the opposite edges alternately to bear

on the strop so that they are sharpened thereby as the to and fro movements of the box draw the blade back and forth along the strop.

5 From the foregoing it will be seen that I have devised a simple, practical and convenient stropping device for safety razor blades.

What I claim as my invention is:—

- 10 1. A razor stropping device comprising, a strop, a box movable back and forth along said strop, a rocking member pivoted within the box transversely of the strop, a blade carrier adapted to detachably hold a double 75
15 edged razor blade removably mounted in said rocking member, and means for rocking the said member whereby the opposite edges of the blade are carried alternately into stropping contact with the strop, said 80
20 means comprising a longitudinally movable bottom slide plate carried by the box, and fulcrumed levers the lower ends of which are connected to said plate and their upper ends to the rocking member.
25 2. A razor stropping device comprising, a strop, a box movable back and forth along the strop, a longitudinally slotted transverse plate bent at its opposite ends to form side plates having downwardly extending 85
30 arms, said side plates being pivotally connected to the box and having slots communicating with the plate slot and wider than the same, a blade carrier adapted to detachably hold a double edged razor blade and 90
35 insertable in the side and transverse plate slots to slidably engage the transverse plate, and means for rocking the said side plates about their pivots to carry the opposite edges of the blade alternately into stropping 95
40 contact with the strop, said means comprising a longitudinally movable bottom slide plate carried by the box, and fulcrumed levers the lower ends of which are connected to the said slide plate and their upper ends to the side plate arms.
45 3. A razor stropping device comprising, a strop, a box movable back and forth along the strop, a longitudinally slotted transverse plate bent at its opposite ends to form side 100
50 plates having downwardly extending arms, said side plates being pivoted to the box and having slots communicating with the plate slot and wider than the same, a bar provided with a hook at one end and adapted to receive a double edged razor blade and a plate 105
55 hinged to the bar, said plate and bar being adapted to grip the blade between them and spaced so that the bar and blade engage slidably the transverse plate when the bar is inserted in the side plate slots, a locking 110
60 bar mounted on the hinged plate capable of being moved into engagement with the hook aforesaid to detachably lock the bar and the plate together, and means for rocking the said transverse plate and blade to carry the opposite edges of the blade alternately into stropping contact with the strop, said means comprising a longitudinally movable bottom slide plate carried by the box, and fulcrumed levers the lower ends of which are connected to the said slide plate and their upper ends to the side plate arms.
65 4. A razor stropping device comprising, a 115
strop, a box movable back and forth along the strop having an opening in one side, a longitudinally slotted transverse plate disposed within the box opposite said opening, bent at its opposite ends to form side plates 120
70 having downwardly extending arms, said 125
75

movable bottom slide plate carried by the box, and fulcrumed levers the lower ends of which are connected to the said slide plate and their upper ends to the side plate arms.

4. A razor stropping device comprising, a strop, a box movable back and forth along the strop, a longitudinally slotted transverse plate bent at its opposite ends to form side plates having downwardly extending arms, said side plates being pivoted to the box and having slots communicating with the plate slot and wider than the same, a bar adapted to receive a double edged razor blade and a plate hinged to the bar, said plate and said bar being adapted to grip the blade between them and spaced so that the bar and blade engage slidably the transverse plate when the bar is inserted in the side plate slots, means for detachably connecting the hinged plate to the bar, and means for rocking the transverse plate and blade to carry the opposite edges of the blade alternately into stropping contact with the strop, said means comprising a longitudinally movable bottom slide plate carried by the box adapted to lie in the palm of the hand having sides adapted to be gripped between the thumb and fingers, and fulcrumed levers the lower ends of which are connected to the said slide plate and their upper ends to the side plate arms.

5. A razor stropping device comprising, a strop, a box movable back and forth along the strop, a longitudinally slotted transverse plate bent at its opposite ends to form side plates having downwardly extending arms, said side plates being pivoted to the box and having slots communicating with the plate slot and wider than the same, a bar provided with a hook at one end and adapted to receive a double edged razor blade and a plate hinged to the bar, said plate and bar being adapted to grip the blade between them and spaced so that the bar and blade engage slidably the transverse plate when the bar is inserted in the side plate slots, a locking bar mounted on the hinged plate capable of being moved into engagement with the hook aforesaid to detachably lock the bar and the plate together, and means for rocking the said transverse plate and blade to carry the opposite edges of the blade alternately into stropping contact with the strop, said means comprising a longitudinally movable bottom slide plate carried by the box, and fulcrumed levers the lower ends of which are connected to the said slide plate and their upper ends to the side plate arms.

6. A razor stropping device comprising, a strop, a box movable back and forth along the strop having an opening in one side, a longitudinally slotted transverse plate disposed within the box opposite said opening, bent at its opposite ends to form side plates having downwardly extending arms, said

side plates being pivoted to the box and having slots communicating with the plate slot and wider than the same, said plate slots being also opposite the box opening, a cover for said opening provided on its inner side with a bar hinged to it adapted to receive a double edged razor blade and a plate rigidly secured to the cover, said plate and bar being adapted to grip the blade between them and spaced so that the bar and blade engage slidably the transverse plate when inserted through the box opening to seat the bar in the side plate slots, means for detachably securing the hinged plate to the bar, and means for rocking the transverse plate and blade to carry the opposite edges of the blade alternately into stropping contact with the strop, said means comprising a longitudinally movable bottom slide plate carried by the box adapted to lie in the palm of the hand having sides adapted to be gripped between the thumb and fingers, and fulcrumed levers the lower ends of which are connected to the said slide plate and their upper ends to the side plate arms.

7. A razor stropping device comprising, a strop, a box movable back and forth along the strop, a rocking member pivoted within the box transversely of the strop, a blade carrier adapted to detachably receive a double edged razor blade removably mounted in said rocking member, levers fulcrumed on the box the upper ends of which are connected to said rocking member, and a bottom slide plate carried by the box to which the lower ends of said levers are connected, said slide plate being longitudinally movable independently of the box a distance sufficient

to rock the said levers and said rocking member to carry the opposite edges of the blade alternately into stropping contact with the strop and being then engageable with the box to carry it along the strop.

8. A razor stropping device comprising, a box having opposite end slots and provided with a roller at each end adjacent the underside of its top plate and a pair of rollers intermediate its length, the upper periphery of each middle roller being in the same plane as the lower periphery of each end roller, a strop passed around the end rollers and carried back around the middle rollers to form parallel stropping portions, said strop having its ends extending through the said end slots, a rocking member pivoted within the box transversely of the strop, a blade carrier adapted to detachably receive a double edged razor blade removably mounted in said rocking member and disposed between the parallel stropping portions, levers fulcrumed in the box the upper ends of which are connected to said rocking member, and a bottom slide plate carried by the box to which the lower ends of said levers are connected, said slide plate being longitudinally movable independently of the box a distance sufficient to rock the levers and rocking member to carry the opposite edges of the blade alternately into stropping contact with the said parallel stropping portions and being then engageable with the box to carry it along the strop.

In testimony whereof I affix my signature at the city of Vancouver, B. C., this 12th day of April, 1922.

JOSEPH ERNEST THORPE.
